CLAIM

The ornamental design for a remote control for water heater, as shown and described.

DESCRIPTION

1. Remote control for water heater

1.1 : Perspective

1.2 : Front

1.3 : Top

1.4 : Right

1.5 : Left

The bottom view is omitted since it is symmetrical to the top view; the broken lines in the drawings form no part of the claimed designs; the dashed-dotted lines represent the unclaimed boundaries.
